(57) **CLAIM**

We claim the ornamental design for a pair of wireless earphones, as shown and described.

DESCRIPTION

FIG. 1 is a front elevational view of a pair of wireless earphones according to the new design;

FIG. 2 is a rear view thereof;

FIG. 3 is a right-side view thereof;

FIG. 4 is a left-side view thereof;

FIG. 5 is a top view thereof;

FIG. 6 is a bottom view thereof;

FIG. 7 is a rear-right-side view thereof; and,

FIG. 8 is a front-top-left-side view thereof.

The broken lines shown in the drawings depict portions of the pair of wireless earphones that form no part of the claimed design.
